UNITED STATES PATENT OFFICE

132,096

DESIGN FOR A UTILITY STAND

Iver W. Cady, Lynwood, Calif.

Application September 24, 1941, Serial No. 103,467

Term of patent 7 years

To all whom it may concern:

Be it known that I, Iver W. Cady, a citizen of the United States, residing at Lynwood, in the county of Los Angeles and State of California, have invented a new, original, and ornamental Design for Utility Stands, of which the following is a specification, reference being had to the accompanying drawing, forming part thereof.

The figure is a perspective view of a utility stand, showing my new design.

I claim:

The ornamental design for a utility stand, substantially as shown.

IVER W. CADY.
